HOLLOW SIX-SIDED FILE

Elwin Theobald, 4631 Solano Way, Fair Oaks, Calif.
95628, and Phillip R. Andrews, 5700 55th St., Sacramento, Calif. 95824

Filed Sept. 29, 1967, Ser. No. 8,784

Term of patent 14 years

(Cl. D37—1)

FIG. 1

FIG. 2

FIG. 3

FIGURE 1 is a perspective view from one end showing the one end and four sides of our new design for a hollow six-sided file;

FIGURE 2 is a perspective view showing the other end and the remaining two sides of the file of FIGURE 1; and

FIGURE 3 is an enlarged cross-sectional view thereof. The incomplete showing of the external surfaces of the hollow six-sided file is understood to be representative of a conventional abrasive surface and continuous thereover.

We claim:

The ornamental design for a hollow six-sided file, substantially as shown and described.
